UNITED STATES PATENT OFFICE.

MATHER W. SHERWOOD, OF FRANKLIN, PENNSYLVANIA, ASSIGNOR TO CHICAGO
PNEUMATIC TOOL COMPANY, OF CHICAGO, ILLINOIS, A CORPORATION OF NEW
JERSEY.

PNEUMATIC TOOL.

1,157,430.

Specification of Letters Patent.

Patented Oct. 19, 1915.

Application filed February 2, 1914. Serial No. 816,085.

To all whom it may concern:

Be it known that I, MATHER W. SHERWOOD, a citizen of the United States, residing at Franklin, in the county of Venango 5 and State of Pennsylvania, have invented certain new and useful Improvements in Pneumatic Tools, of which the following is a specification.

My invention relates to a tool operated 10 by a motive fluid such as compressed air and the object thereof is to provide a simple and efficient construction and new mode of operation of valve mechanism and also to improve the means whereby the same may 15 be arranged and assembled in the tool and be removed therefrom whenever desired.

In the drawings Figure 1 is a central longitudinal section of a pneumatic tool in the form of a hand drill embodying my invention; Fig. 2 a detail section showing means for fastening or clamping the parts together; Fig. 3 an elevation of the cylinder or body of the valve cage illustrating the preferred form thereof and Fig. 4 a section 25 on the line 4—4 of Fig. 3.

Inasmuch as my invention relates to the valve mechanism of a tool it is evident that the other parts of such tool may partake of different forms and be of different types 30 but for convenience and definiteness of description and disclosure of my invention I have chosen to illustrate and will hereinafter describe the same as embodied in a pneumatic tool of the hand-drill type, without intention of limiting myself thereto.

The pneumatic tool herein shown comprises a main cylinder 1, a handle 2 clamped thereto in the manner hereinafter described, a piston 3 reciprocable within the cylinder, 40 a striking piece or anvil 4 against which the blows of the piston are transmitted through the medium of the piston stem 3^a, and the working tool which is here in the form of a drill bit or steel 5. This tool is of the type 45 having a rotary drill chuck 6 but inasmuch as this feature is immaterial to the present invention the same will not be described. The cylinder 1 contains a piston chamber 1^a having suitable ports and passages for the 50 admission and exhaust of pressure to and from opposite ends including a rear port 7 and a front port 8, the former communicating directly with a valve chamber 9 formed in the body of the cylinder and the latter 55 indirectly therewith through the passage 10.

The piston chamber is also provided with exhaust ports 11 and exhaust grooves 11^a communicating therewith, and also with exhaust grooves and ports 11^b.

Within the valve chamber 9 is contained 60 the distributing valve mechanism which controls the admission of the live air through the supply passage 12 to opposite ends of the piston chamber for reciprocating the piston. This valve mechanism preferably of 65 the ball type shown, comprises a valve cage which is removably positioned in the front end of the valve chamber and contains a hollow ball 13 acting as a valve. The ball cage consists of a shell 14 and the two end 70 pieces 15 and 16 each provided with the central ports 17 and 18 and each acting as a seat with respect to the ball valve. Each seat is provided with a marginal flange fitting accurately within the valve chamber 75 and extends into the shell. A series of ports 19 extend through the shell and communicate between the annular space 20 surrounding the valve cage and the interior of such cage, such annular space of course communicating with the source of motive fluid supply. When the ball valve 13 is in its left hand position shown in Fig. 1 the communication from the source of supply to the front 80 end of the piston chamber is open, the route being through the connection 12, annular space 20, interior of the valve cage, port 17, passage 10 and port and passage 8. At the same time, the live motive fluid is present in the annular space 13^a in the left hand 85 corners of the interior of the valve cage and on the left hand face of the ball, with the result hereinafter explained. When the ball valve is in its right hand position the live motive fluid is admitted from the source of 90 supply through the connection 12, annular space 20, interior of the valve cage, port 18, left hand end of valve chamber 9 and port 7 to the rear end of the piston chamber. In 95 this right hand position of the ball, the live motive fluid is present in the annular space 13^b in the right hand corners of the interior of the valve cage and on the right hand face of the ball.

Describing the mode of operation of the 100 valve mechanism and starting with the position of the parts indicated in Fig. 1, the live motive fluid is being admitted to the front end of the piston chamber with the result 105 that the piston will be forced to the rear end 110

of the chamber. As soon as the front end of the piston has cleared the exhaust groove 11^a, the pressure in the front end of the piston chamber and also in the supply passages 8 and 10 will be rapidly and materially decreased, much more rapidly than it can be supplied through the ports 19. Consequently the live motive fluid which is present in the space 13^a will exert its pressure against the ball and force the same to the right thereby closing the port 17 and opening the port 18. The live motive fluid will thereupon pass to the rear end of the piston chamber and drive the piston forwardly to deliver its blow upon the anvil 4 which in turn delivers the blow to the drill bit 5. When the piston in its forward travel uncovers the other exhaust groove 11^b the pressure in the rear end of the piston chamber and also in the communicating passages will be rapidly and materially decreased, whereupon the live motive fluid in the space 13^b will exert its pressure against the ball and force the latter back to the starting position shown in Fig. 1, thereby completing a full cycle of operation. It will be understood that the ports 19 are of limited carrying capacity as compared with the large ports 8 and 10 and 17 also the exhaust grooves and passages.

In so far as the feature of the valve movement in its broader aspect is concerned, the precise shape of the valve proper is immaterial so long as it is such that the movement thereof in the manner described is effected, but I prefer to employ a ball as such valve.

By preference the ports 19 in the valve cage are formed at an angle to the longitudinal axis thereof as shown in Fig. 4 so that the current of incoming motive fluid will have a tendency to properly rotate the valve so that it will be constantly changing its position with respect to the valve seat in order to avoid any possible wearing of the seating surface of the ball in any one place.

As hereinbefore stated the valve cage fits into the forward end of the valve chamber. This fit is a loose one, the parts of the cage being assembled and pushed into such end of the valve chamber. In order to hold the parts of the valve cage in their assembled condition and with yielding pressure I interpose between the valve seat 16 and the outer end of the valve chamber a coiled spring 21. By preference I provide at the outer end of the valve chamber a cap 22 closing such end of the chamber and forming the outer abutment for the coiled spring.

The front head 26 is by preference clamped to the cylinder by suitable bolts such as the side bolts 23 passing through the lug 24 of the cylinder and the lug 25 formed on the front head. The front end of each side bolt carries the usual cushion spring 27

and the end nut 28. The handle is by preference bolted to the cylinder by bolts 29 of which only one is shown, these bolts passing through the lugs 30 and 31 on the handle and cylinder respectively. In practice the valve mechanism is assembled in the position shown in Fig. 1 and in the act of clamping the handle to the cylinder and back head by means of the side bolts the end cap 22 is forced and held in place and consequently the parts of the valve mechanism are retained in place through the medium of the coiled spring 21. If desired, the end cap 22 could be made to screw into the rear end of the valve chamber but I prefer the sliding fit shown in Fig. 1 which permits of ready assembling and disassembling of the parts.

I claim:

1. The combination of a cylinder having ports and passages for the admission and exhaust of motive fluid, a piston reciprocable in the cylinder, and valve mechanism controlling said ports and passages comprising a valve chamber having oppositely arranged seats provided with ports and a valve arranged to vibrate between such seats and to alternately close the ports in the seats, the valve chamber having a motive fluid supply port of less carrying capacity than the ports in the seat and the exhaust port and passage of the cylinder, the valve and its chamber being constructed to provide a space for the motive fluid at each end of the chamber between it and the valve when at such end, whereby the motive fluid in such space will force the valve to the opposite end of the valve chamber when such latter end is at exhaust.

2. The combination of a cylinder having ports and passages for the admission and exhaust of motive fluid, a piston reciprocable in the cylinder, and valve mechanism controlling said admission ports and passages comprising a valve chamber having oppositely arranged seats provided with ports and a valve arranged to vibrate between such seats and to alternately close the ports in the seats, said valve being a ball and the valve chamber having a motive fluid supply port of less carrying capacity than the ports in the seat and the exhaust port and passage of the cylinder, the ball valve in each of its end positions providing a space for the motive fluid between it and the corners of the valve chamber, whereby the valve is forced by the motive fluid in such space at one end of the valve chamber to the opposite end thereof.

3. The combination of a cylinder having ports and passages for the admission and exhaust of motive fluid, a piston reciprocable therein, and valve mechanism controlling said admission ports and passages comprising a cage formed of a shell and two valve

seats provided with ports, a valve located within the shell and arranged to vibrate between the seats and to govern the ports therein, such valve and shell being constructed to provide a space for the motive fluid at each end of the shell between it and the seats, whereby the valve is forced by the motive fluid in such space at one end of the shell to the opposite end thereof, said shell having openings for the admission of the motive fluid.

4. The combination of a cylinder having ports and passages for the admission and exhaust of motive fluid, a piston reciprocable in the cylinder, and valve mechanism controlling said admission ports and passages comprising a cage formed in three separable sections consisting of two valve-seats and a shell, a valve therein, said cylinder having a valve chamber to receive the cage, and yielding means for holding said sections together and the entire valve cage in position within the valve chamber.

5. The combination of a cylinder having ports and passages for the admission and exhaust of motive fluid, a piston reciprocable in the cylinder, and valve mechanism controlling said admission ports and passages comprising a cage formed in three separable sections consisting of two valve seats and a shell, a valve therein, said cylinder having a valve chamber to receive the cage, and a spring for holding the valve cage in position within the valve chamber.

35 6. The combination of a cylinder having ports and passages for the admission and exhaust of motive fluid, a piston reciprocable in the cylinder, and valve mechanism controlling said admission ports and passages comprising a cage formed in three separable sections consisting of two valve seats and a shell, a valve therein, said cylinder having a valve chamber to receive the cage, and a spring bearing directly against one of the 45 valve seats for holding the valve cage in position within the valve chamber.

7. The combination of a cylinder having ports and passages for the admission and exhaust of motive fluid, a piston reciprocable in the cylinder, and valve mechanism controlling said admission ports and passages comprising a cage formed in three separable sections consisting of two valve seats and a

shell, a valve therein, said cylinder having a valve chamber to receive the cage, a cap closing an end of the valve chamber, and a spring arranged within such chamber between said cap and valve cage. 55

8. The combination of a cylinder having ports and passages for the admission and exhaust of motive fluid, a piston reciprocable in the cylinder, and valve mechanism controlling said admission ports and passages comprising a cage formed in three separable sections consisting of two valve seats and a shell, a valve therein, said cylinder having a valve chamber to receive the cage, a cap closing an end of the valve chamber and having a sliding fit therein, and the valve cage also having a sliding but air-tight fit within the chamber and located at the other end thereof, and means for holding the valve cage in position. 60

9. The combination of a cylinder having ports and passages for the admission and exhaust of motive fluid, a piston reciprocable in the cylinder, and valve mechanism controlling said admission ports and passages comprising a cage formed of two valve seats and a shell, a valve therein, said cylinder having a valve chamber to receive the cage, a cap closing an end of the valve chamber and having a sliding fit therein, and the valve cage also having a sliding but air-tight fit within the chamber and located at the other end thereof, and a spring arranged between said cage and cap. 75

10. The combination of a cylinder having ports and passages for the admission and exhaust of motive fluid, a piston reciprocable in the cylinder, and valve mechanism controlling said admission ports and passages comprising a cage formed of two valve seats and a shell, a valve therein, said cylinder having a valve chamber to receive the cage, a cap closing an end of the valve chamber and having a sliding fit therein, a valve cage within the chamber, a spring between the cap and cage, and a handle clamped to the cylinder and bearing against the cap to hold it in place. 90
